[57] CLAIM

The ornamental design for a tennis ball container, as shown and described.

DESCRIPTION

FIG. 1 is a perspective view of a tennis ball container showing our new design;

FIG. 2 is a side elevation view thereof, the three repeating sides of the tennis ball container being the same in appearance;

FIG. 3 is another side elevation thereof;

FIG. 4 is a top plan view thereof; and,

FIG. 5 is a bottom view thereof.

The broken lines in FIG. 1 showing tennis balls are for illustrative purpose only and form no part of the claimed design.
